UNITED STATES PATENT OFFICE.

FRANK B. HOWELL, OF BUFFALO, NEW YORK, ASSIGNOR TO AMERICAN RADIATOR COMPANY, OF CHICAGO, ILLINOIS, A CORPORATION OF NEW JERSEY.

BOILER.

Application filed December 31, 1920. Serial No. 434,262.

My invention relates to improvements in boilers, more particularly to boilers used in connection with heating systems, and the same has for its object to provide a boiler 5 with an auxiliary supply of pre-heated air so arranged that a proper volume of air will be supplied continuously to the combustion chamber of the boiler during the operation thereof.

10 Another object is to provide a boiler having a fuel charging opening with a closure for said opening which is so constructed that the auxiliary supply of air will pass therethrough into the boiler.

15 Another object is to provide a boiler having a fuel receptacle in which the undue distillation of the fuel within the receptacle is prevented.

Another object is to provide a boiler 20 having a fuel receptacle with an auxiliary air supply so arranged as to prevent the heat of the flue gases from being transmitted to the fuel in the receptacle.

Another object is to provide a boiler 25 having a plurality of flues or heat-receiving portions which are separated from the fuel receptacle by air cells or chambers forming a partition extending the entire length of the fuel receptacle, and which serve to prevent, 30 in a measure, the overheating of said fuel receptacle, and to conduct auxiliary air to the combustion chamber.

Another object is to provide a boiler having a fuel receptacle in which conduits for 35 an auxiliary air supply are formed integrally with the boiler or boiler sections, and positioned between the fuel receptacle and the flue or flues.

Other objects will in part be obvious, and 40 in part be pointed out hereinafter.

To the attainment of the aforesaid objects and ends, my invention consists in the novel details of construction, and in the combination, connection and arrangement of parts 45 hereinafter more fully described and then pointed out in the claim.

In the accompanying drawings showing an 50 illustrative embodiment of the invention and in which, for purposes of illustration, the invention is shown in connection with a boiler of the sectional type—

Figure 1 is a front view showing one form of boiler constructed according to and embodying my said invention;

55 Fig. 2 is a top view thereof;

Fig. 3 is a vertical section taken on the line 3—3 of Figure 1;

Fig. 4 is a horizontal section taken on the line 4—4 of Fig. 3; and

Fig. 5 is an enlarged detail sectional view 60 showing the construction of the magazine cover, and the air inlets thereof.

Referring to the drawings, the boiler comprises hollow end sections 10, and a plurality of hollow intermediate sections each of which 65 is composed of a front member 12 and a rear member 13. Adjacent their upper and lower portions said sections are provided with registering openings within which are secured nipples 15, thereby providing for the 70 free circulation of water or fluid throughout the boiler, which is provided with a water-inlet or return 16 and a water outlet 17. The assembled sections of the boiler are preferably 75 enclosed by a casing 20.

Each of the front members 12 comprises a vertical upper portion 21 and a rearwardly inclined lower portion 22 which serves as a support for the fuel which is undergoing combustion. The upper portion 21 has laterally extending ribs 23, the edges of which 80 engage the edges of the corresponding ribs of adjacent sections to form air tight joints therewith. The lower portion 22 has a plurality of laterally extending ribs 24 which 85 register with the corresponding ribs of adjacent sections to form a plurality of air inlets 24^a for the admission of primary air to support combustion of the incandescent fuel.

Each of the rear members 13 has a forwardly extending portion 25 which overhangs the inclined lower portion 22 of its complementary front portion 12. Each member 13 is provided at the top and back thereof with transversely-extending peripheral ribs 26, 90 and at the front wall of its forwardly-extending portion with transversely-extending ribs 27, the upper ends of which terminate at points below the horizontal peripheral ribs 26 at the top of the member, to form openings 28 for a purpose hereinafter described. Extending downwardly from the peripheral ribs 26 at the top of each member 13 are transversely-extending ribs 29 which are positioned to the rear of the ribs 27 and are substantially parallel therewith. Each member 13 is provided intermediate its front and back with inclined upwardly and forwardly 100 extending ribs 30 terminating below the top of the boiler.

When the sections are assembled, the corresponding ribs of adjacent sections engage one another to form air chambers or conduits 31, and reversible flues 32 between the water compartments of adjacent sections, which conduits and flues extend from the combustion chamber 33 formed by the lower portions 22 of the front members 12 and the over-hanging forwardly extending portions 25 of the rear members 13. The air chambers or conduits 31 serve to admit an auxiliary supply of air to the combustion chamber 33; the air entering the upper ends of the conduits through the openings 28, and the flues 32 serving to conduct the products of combustion to the collecting flue 34 formed adjacent to the lower ends of the members 13 and thence to the smoke pipe 35.

The front walls of the forwardly extending portions 25 of the rear member 13, together with the upper portions 21 of the front members 12, form a fuel receptacle 36 into which the fuel is delivered through a charging opening 37 preferably arranged in the upper portion of the casing 20. Positioned within the opening 37 is a frame 38 having an upwardly extending flange 39 provided with one or more cutaway portions 40. Pivotally mounted on the frame 38 is a cover 41 adapted to seat upon the flange 39, and having a downwardly extending flange 42 which, when the cover is closed, is spaced from the flange 39 to permit a constant supply of air to pass between the flanges 39 and 42, and through the cutaway portion 40 into the upper end of the fuel receptacle 36 from which it passes through the openings 28 into the upper ends of the conduits 31. In order to prevent the fuel from passing into the upper ends of the conduits 31, suitable baffles 43 are provided which are positioned in front of the openings 28.

In order to provide for the cleaning of the flues 32, the peripheral ribs may be cut away to form openings 44 normally closed by covers 45, which openings register with a large opening 46 in the casing provided with a single cover 47.

In operation, the fuel column is supported upon the lower portion 22 of the front members 12, and by the bed of ashes in the ash pit, the feed of fuel being maintained constant by the reserve fuel contained within the receptacle 36. The main supply of air necessary to support combustion passes through the spaces 24 between the ribs 24, and into the burning fuel, and the products of combustion pass from the combustion chamber, through the flues 32 and openings 34 into the smoke pipe 35. As the products of combustion pass from the combustion chamber into the flues, auxiliary air will be drawn downward through the conduits 31, the proper amount of air being admitted to the upper ends of the conduits through the air passage formed

between the frame 38 and the door 41. As the air passes downward through the conduits, it will be gradually and increasingly heated by the hot gases passing through the flues until it enters into the combustion chamber, at which time its temperature will be such as to insure proper combustion of the gases liberated from the incandescent fuel and prevent the undue cooling of the combustible gases. As the air conduits 31 are positioned between the rear members 13 of the intermediate sections, the supply of auxiliary air which is delivered into the combustion chamber will be uniformly distributed throughout the width thereof and thus insure a uniform mixing with and combustion of the gases liberated from the fuel.

As the air upon entering the conduits 31 is at a lower temperature as compared to the temperature of the flue gases, and does not attain its maximum temperature until it reaches the combustion chamber, it will serve as a heat insulating medium to prevent the heat from being transmitted to the fuel within the fuel receptacle 36, and thereby prevent any undue distillation of the fuel therein.

Having thus described my said invention, what I claim and desire to secure by Letters Patent is:—

A boiler comprising end sections and a plurality of intermediate sections, each of said intermediate sections comprising a front member and a back member arranged in spaced relation relative to each other; said back members each having an intermediate forwardly-projecting angular portion and forming jointly with said front members a vertical tapering fuel magazine extending transversely of the boiler, said front members each having an inwardly and downwardly inclined grate portion extending below the projecting angular portion of its respective back member and forming therewith a downwardly flaring fuel receptacle and combustion chamber; a series of narrow vertical flues formed intermediate said back members to the rear of said fuel receptacle and extending longitudinally from said fuel receptacle towards the back of the boiler, and the upper portions of each of said back members having a pair of spaced ribs arranged along its front edge upon opposite sides thereof registering with corresponding ribs of the contiguous back members to form a series of relatively narrow flues for the introduction of secondary air between said fuel magazine and the flues disposed to the rear of and extending from said combustion chamber to the smoke outlet of the boiler, substantially as specified.

Signed at the city of Buffalo, Erie County, in the State of New York, this 23d day of November, one thousand nine hundred and twenty.

FRANK B. HOWELL.
